BODY VIBRATOR

Wesley D. Spencer, James C. Zancker, Milton M. Kauffman, and Alphonso T. D. Meyer, Los Angeles, Calif., assignors to Vibramotor Company, Los Angeles, Calif., a corporation of California

Application May 17, 1939, Serial No. 274,154

8 Claims. (Cl. 128—33)

Our invention relates to a vibrator that is electrically operated for vibrating a human body by the person standing on a platform that is vibrated electrically and the objects of our invention are:

First, to provide a body vibrator of this class which is very small and compact so that it may be readily used in a bathroom, bedroom or the like the same as scales;

Second, to provide a body vibrator of this class by the use of which the person to be treated stands upright on a platform and the platform is vigorously vibrated, thus vibrating the whole body of the person;

Third, to provide a vibrator of this class in which the platform is secured directly to the one side of a laminated armature;

Fourth, to provide a body vibrator of this class in which the platform is supported resiliently at one end upon a resiliently supported base and is supported on its other end on a laminated armature for an electro-magnet;

Fifth, to provide a body vibrator of this class in which the electromagnet and armature are supported and positioned on an open bracket in cushioned relation with said bracket and with each other; and

Sixth, to provide a body vibrator of this class which is very simple and economical of construction, easy to operate, efficient in its action and which will not readily deteriorate or get out of order.

With these and other objects in view as will appear hereinafter, our invention consists of certain novel features of construction, combination and arrangement of parts and portions as will be hereinafter described in detail and particularly set forth in the appended claims, reference being had to the accompanying drawing and to the characters of reference thereon which form a part of this application in which:

Figure 1 is a top or plan view of our body vibrator and showing a cover casing in section taken from the line 1—1 of Fig. 2; Fig. 2 is a longitudinal sectional view taken from the line 2—2 of Fig. 1; Fig. 3 is an end view just inside of one side of the casing taken from the line 3—3 of Fig. 2; Fig. 4 is a sectional view taken from the line 4—4 of Fig. 2 and Fig. 5 is an enlarged fragmentary sectional view taken from the same plane as Fig. 2.

Similar characters of reference refer to similar parts and portions throughout the several views of the drawing:

The base member 1, platform member 2, platform and base connection 3, platform supporting

bracket 4, electro-magnet winding 5, electro-magnet laminated core 6, electro-magnet laminated core adjusting bolts 7, laminated armature 8, laminated armature cushion envelope 9, electric conductors 10 and cover casing 11 constitute the principal parts and portions of our body vibrator.

The base member 1 includes a substantially rectangular shaped plate portion 1a provided with a central hole 1b and with an upwardly extending ledge 1c along its back side. It is provided with two backwardly extending channel members 1d and 1e at its opposite sides which terminate with a cross bar 1f which extends across the back end and preferably integral with the members 1d and 1e, and this base member is supported by means of a plurality of rubber cushions 1g, one at each corner and two intermediate the ends at the opposite site sides.

Mounted centrally over the opening 1b on the portion 1a of the base member 1 is the platform supporting bracket 4 which is provided with a base portion 4a which is secured to the portion 1a by means of screw bolts 4b. It is provided with a central opening 4c and above this opening with a backwardly extending ledge 4d, shown best in Fig. 2 and with opposite end walls 4e.

Mounted on the base portion 4a of the bracket 4 and positioned centrally is the laminated armature 8 which is provided with a non-inflatable cushion covering in the form of an envelope, preferably soft rubber, designated 9 and including a substantially heavy base portion 9a below the armature 8 provided with grooves 9b in its upper surface on which to rest the lower side of the armature 8. At its upper side it is provided with a relatively thin cover portion 9c which is corrugated at its upper side at 9d. Corrugations 9d are also provided at the lower surface of base portion 9a as seen in Figs. 4 and 5.

Positioned adjacent to and above and preferably resting on this corrugated portion 9d of the cushion 9 is an electro-magnetic laminated core 6 which is provided with a central portion 6a and with two side portions 6b and 6c and wound around the central portion 6a of this core 6 is an electro-magnet winding 5 which is wound through the opening 5a at one side and this winding 5 is connected electrically with a source of electrical energy to the electric conductors 10, which source of electrical energy is not shown. The core 6 is supported on the bracket 4 by means of bolts 6d which are mounted in slotted holes 4f in the bracket 4 which permit the shifting of the bolts upwardly and downwardly. These bolts pass through the core 6 as shown best in Fig. 2 of the

drawing. This core is also supported by means of clamp plates 6e which are supported by bolts 6f extending through the bracket 4.

Screw threaded in the ledge 4d of the casing 4 are adjusting bolts 7. Their extended ends are adapted to rest against the upper side of the core 6 and are adapted to press the core 6 downwardly adjacent the cushion portion 9c and this provides adjusting means for adjusting the vibration strokes to provide the best results. These bolts 7 are provided with lock nuts 7a for holding the bolts from turning after the adjustment is made.

Mounted in the laminated armature 8 are two bolts 8a which are screw threaded into the solid end portion 2a of the platform member 2. This portion 2a is provided with an extended flange portion 2b which extends under the armature 8 some distance and rests upon the rubber cushion 9, shown best in Fig. 2 of the drawing.

Extending from the portion 2a backwardly on an upward incline is a lug portion 2c which is reinforced by ribs 2d at its lower side which terminates with a flange 2e on the front side of the platform 2, as shown best in Fig. 2 of the drawing.

Extending backwardly from this portion 2e is a rectangularly shaped portion 2f of the platform 2. It is provided on its upper surface with a knurled portion outlined by the lines 2g, shown best in Fig. 1 of the drawing. This platform portion 2f is provided with a downwardly curved portion 2h which is provided with an angular beveled portion 2i on its lower side to which is secured platform base connection 3 by means of screws 3a. This connection member 3 is provided with an angular forwardly extending portion 3b which extends forwardly in a groove so that it is flush with the lower side of the member 1f. This portion 3b is secured by means of screws 3c. This member 3 is preferably made of spring material which permits vibration movement of the platform 2 vibrated by the laminated armature 8 in cooperation with a vibrator including the core 6 and winding 5 and cushioned by the cushion member 9 surrounding the laminated armature 8 and positioned between it and its base and between it and the core 6.

Positioned over the portion 1a of the base member 1 and over the vibrating apparatus and enclosing the same is a cover casing 11 which is open at its lower side and adapted to fit around the portion 1a and extend backwardly of the ledge 1c and only extends downwardly at the back side to near the platform member 2, all as shown best in Fig. 2 of the drawing.

Though we have shown and described a particular construction, combination and arrangement of parts and portions we do not wish to be limited to this particular construction, combination and arrangement, but desire to include in the scope of our invention the construction, combination and arrangement substantially as set forth in the appended claims.

Having thus described our invention, what we claim as new and desire to secure by Letters Patent is:

1. In a body vibrator of the class described, a base member, a supporting bracket rigidly mounted on said base member near one end and provided with a base portion, a non-inflatable cushion member mounted on said base portion in the form of an envelope, an armature mounted in the envelope portion of said cushion member, and a platform with one end secured directly to one vertical side of said armature and its other

end resiliently supported on the opposite end of said base member.

2. In a body vibrator of the class described, a base member, a supporting bracket rigidly mounted on said base member near one end and provided with a base portion, a non-inflatable cushion member mounted on said base portion in the form of an envelope, an armature mounted in the envelope portion of said cushion member, a platform with one end secured directly to one vertical side of said armature and its other end resiliently supported on the opposite end of said base member, and an electro-magnet positioned in said supporting bracket with its core adjacent to said armature but cushioned and spaced therefrom by said cushion envelope.

3. In a body vibrator of the class described, a base member, a supporting bracket rigidly mounted on said base member near one end and provided with a base portion, a non-inflatable cushion member mounted on said base portion in the form of an envelope, an armature mounted in the envelope portion of said cushion member, a platform with one end secured directly to one vertical side of said armature and its other end resiliently supported on the opposite end of said base member, an electro-magnet positioned in said supporting bracket with its core adjacent to said armature but cushioned and spaced therefrom by said cushion envelope, and means for adjusting the position of said electro-magnet core relative to said armature.

4. In a body vibrator of the class described, a base member, a supporting bracket rigidly mounted on said base member near one end and provided with a base portion, a non-inflatable cushion member mounted on said base portion in the form of an envelope, an armature mounted in the envelope portion of said cushion member, a platform with one end secured directly to one vertical side of said armature and its other end resiliently supported on the opposite end of said base member, an electro-magnet positioned in said supporting bracket with its core adjacent to said armature but cushioned and spaced therefrom by said cushion envelope, means for adjusting the position of said electro-magnet core relative to said armature, and a casing covering said electro-magnet and armature and a portion of said platform.

5. In a body vibrator of the class described, a base member including a substantially solid portion at one end and an open outline frame portion at its other end, an electro-magnet and armature supported on said base member, said electro-magnet being rigidly supported thereon, a platform with one end bolted to said armature in substantially the same horizontal plane therewith and a resilient connection connecting the other end of said platform with the open outline frame portion end of said base member for resiliently supporting said platform on said base member.

6. In a body vibrator of the class described, a base member including a substantially solid portion at one end and an open outline frame portion at its other end, an electro-magnet and armature supported on said base member, said electro-magnet being rigidly supported thereon, a platform with one end bolted to said armature in substantially the same horizontal plane therewith, a resilient connection connecting the other end of said platform with the open outline frame portion end of said base member for resiliently supporting said platform on said base member,

said electro-magnet including a core and a winding, said core positioned adjacent to said armature and means engaging said core for adjusting and holding said core tightly in spaced relation with said armature.

7. In a body vibrator of the class described, a base member including a substantially solid portion at one end and an open outline frame portion at its other end, an electro-magnet and armature supported on said base member, said electro-magnet being rigidly supported thereon, a platform with one end bolted to said armature in substantially the same horizontal plane therewith, a resilient connection connecting the other end of said platform with the open outline frame portion end of said base member for resiliently supporting said platform on said base member, said electro-magnet including a core and winding, non-inflatable cushion means interposed between said core and said armature, said core positioned adjacent to said armature and means engaging said core for adjusting and holding said core tightly in relation with said cushion means.

8. In a body vibrator of the class described, a

base member including a substantially solid portion at one end and an open outline frame portion at its other end, an electro-magnet and armature supported on said base member, said electro-magnet being rigidly supported thereon, a platform with one end bolted to said armature in substantially the same horizontal plane therewith, a resilient connection connecting the other end of said platform with the open outline frame portion end of said base member for resiliently supporting said platform on said base member, said electro-magnet including a core and winding, non-inflatable cushion means interposed between said core and said armature, said core positioned adjacent to said armature and means engaging said core for adjusting and holding said core tightly in relation with said cushion means, and a casing covering said electro-magnet, solid portion of said base member and the end of said platform secured to said armature.
